Application October 29, 1953, Serial No. 389,106

6 Claims. (Cl. 255—1)

This invention pertains to apparatus for placing subsurface explosive charges in connection with seismic exploration such as is conducted in prospecting for oil.

If a hole is drilled in mushy or sandy soil, the hole will close up as soon as the drill pipe is removed. It is therefore necessary to leave the drill pipe in the hole as a casing to prevent such collapse of the walls. This is equally true whether the hole is for producing oil or for reception of an explosive charge used in seismographic exploration. However in seismographic work the pipe left in the hole after the charge has been exploded is a pure waste, there being no further need for the hole after the charge has been exploded and the seismograph record made.

The drill pipe if left in the hole as a casing must have a diameter the same size as the desired hole. This means that either the drill pipe must have as large a diameter as the bit, causing considerable friction during drilling, or the bit must be bigger than the desired hole. It costs too much to drill a hole larger than necessary, so the hole is made the same diameter as the pipe. But with the pipe tight in the hole it costs more to pull it out after the charge has been exploded than the pipe is worth. Even if an oversize hole were drilled the pipe would probably be tight in the hole after the charge was exploded.

According to the invention casing is saved by drilling the hole with the explosive charge disposed adjacent the drill bit, instead of lowering it in after the hole has been drilled. Since the charge is then already at the bottom of the hole, the drill pipe above need not be as large in diameter as the bit and is therefore not tight in the hole. This makes it easier to drill the hole and after the hole is drilled the pipe can be disconnected from the bit and easily pulled to the surface.

The ignition cable which must extend from the charge to the surface is placed in the lower end of the drill pipe in the form of a spool, one end being connected to the charge in the drill bit and the other fixed to the spool. Then as the hole is drilled the cable as well as the charge is always at the bottom of the hole. After the hole is drilled to the desired depth, the drill pipe is disconnected from the drill bit and charge and, as the pipe is withdrawn, the spool unwinds and the cable is left in the hole, extending from top to bottom.

For a description of a preferred embodiment of apparatus useful in carrying out the method of the invention, reference will now be made to the accompanying drawings in which:

Figure 1 is a front elevation, largely in section, showing a charge placing apparatus according to the invention;

Figure 2 is a side elevation of a portion of the apparatus shown in Figure 1;

Figure 3 is a horizontal section taken on the plane 3—3 of Figure 1;

Figure 4 is a vertical section showing the apparatus of Figure 1 disposed in a hole in the earth's surface, with the bit detached, the drill pipe raised, and the cable partially unwound; and

Figure 5 is a vertical section similar to Figure 4 but showing the drill pipe completely removed and the cable connected to an electric generator at the surface.

Referring to Figure 1, there is shown a drill bit 10 having holes or nozzles 10a through which water is projected under pressure during the drilling operation. A length of pipe 11 is screwed into the drill bit. A tubular explosive receptacle 12 is disposed inside the pipe 11 and held in place by struts such as 13, 14 (see also Figure 3).

10 The receptacle is filled with explosive not shown. A detonator cap 15 is imbedded in the explosive and thereby insulated against mechanical shocks during drilling. A stopper 16 closes the top of the receptacle for explosive. There is a hole 17 in the stopper through which passes

15 ignition cable 18 which is connected at one end to cap 15.

A pipe 19 is connected to pipe 11 by means of a releasable fastening such as a double bayonet joint, illustrated in Figs. 1 and 2 as comprising radially extending pins 19a on the pipe 11 which are slidable within L-slots 20 19b in the pipe 19. A ring 20 is secured to pipe 19 inside thereof. An O ring 21 of neoprene or other rubber-like material is frictionally held in a groove in the lower face of ring 20 and makes contact with the upper end of pipe 11 to form a liquid tight seal between the two pipes and provide a certain amount of frictional resistance to uncoupling of the bayonet joint.

A tubular housing 22 telescopes over the top of receptacle 12 to the extent permitted by stop ring 23 fastened inside housing 22 a short distance from its lower end.

30 The upper end of the housing is closed by a cone shaped plug 22a fastened thereto. A spool 24 is screwed into plug 22a. Ignition cable or wire 18 is wound on spool 24 and the upper end of this cable is fastened to the spool. A pair of spring fingers 25, 26 are fastened at their upper 35 ends to the side of housing 22, the lower ends of the fingers tending to expand and press outwardly on pipe 19. In the position shown in Figure 1 the fingers serve to position the housing 22 inside pipe 19.

In order to insure that the housing 22 cannot completely separate from the pipe 19, when the pipe 19 is raised as hereinafter described, we provide a safety means comprising a line 27 which is attached at one end to an engaging ring 28 on the top of plug 22a by means of a releasable snap coupling 29. Inside a pipe 30, which is 40 screwed to the top of pipe 19, is secured a bar 31 to which a swivel 32 on the upper end of line 27 is fastened. If for any reason, therefore, the fingers 25, 26 should drop past the rings 20, 21 inside of pipe 19, the housing 22 will be suspended within pipe 19 by means of the line 27. The upper end of the pipe 30 is reduced and is 45 screwed to the drill pipe 33 to complete the drill string.

In assembling the apparatus the housing 22 is placed on top of receptacle 12. Then pipe 19 is placed over the top of the housing, whereby spring fingers 25, 26 first are 50 forced inwardly by rings 20 and 21 to a retracted position and then are permitted to snap outwardly to engage the inner surface of pipe 19. In using the apparatus, water can be circulated down through the drill pipe, out through the holes 10a in the drill bit 10 and back to the surface as usual. The spool housing and explosive receptacle keep the cable and charge dry and, of course, prevent the dynamite charge from being washed away by the circulating water. After the hole has been drilled deep enough pipe 19 is uncoupled from pipe 11 and the 55 drill pipe 33 is raised carrying pipes 30 and 19 with it. Spool housing 22 drops down until the spring fingers 25, 26 engage ring 21 whereupon the cable 18 begins to 60 unwind as shown in Figure 4. Should the fingers fail to hold, the spool will be retained by line 27 though it will 65 then be below pipe 19. On reaching the surface the cable is cut from the spool and connected to generator 34 as 70

shown in Figure 5. The spool can be removed through the top of pipe 19 after unscrewing pipe 30. The drill bit and explosive receptacle and pipe 11 will be destroyed by the explosion of the charge but this loss will be negligible since an inexpensive bit is used for drilling the shallow seismic charge holes. The drill pipe and the spool housing and pipes 19 and 30 will be saved.

The apparatus described can be considerably varied to carry out the method under varying conditions. Various parts shown as separable can be made integral and vice versa. Thus, pipes 30 can be integral with the lower length of drill pipe 33. Pipe 30 can also be integral with pipe 19 and, to facilitate removal of the spool housing, the spring fingers can be reversed to point upwards and be provided with hooks to engage a ring like ring 20 disposed above the level of the housing. A tube could then be placed over the lower end of the housing to compress the fingers to permit withdrawal of the housing. The spool can be revolvably mounted and can be made with either a horizontal or vertical axis. A cone shaped spool could be used to facilitate unwinding. Pipe 19 can fit inside as well as outside pipe 11. A quick make up screw connection of the low reverse torque type known as a safety joint could be substituted for the bayonet joint; or a simple telescoping joint with a friction fit and with some non-circular section, e. g., hexagonal to transmit rotation could be used; or a releasable coupling actuated hydraulically or mechanically from the surface might be desirable in some cases. The pipe 11 and receptacle 12 can be made in short sections fitted together in any desired manner, sufficient sections being used to accommodate the size of explosive charge required. The spool housing for the explosive receptacle can be eccentrically located, e. g., against one side of the pipes therearound, instead of concentric therewith. The bit 10 and pipe 11 can be made integral. But regardless of the details of the apparatus used, the general method remains the same. By means of the method the charge placed in the hole may be of a larger size than could be lowered through the drill pipe in accordance with prior practice.

While a preferred embodiment of the apparatus of the invention has been illustrated and described and as several variations thereof have been described and a preferred procedure for carrying out the method of the invention has been described, it is obvious that many modifications of the invention can be made by one skilled in the art without departing from the spirit of the invention and it is intended to protect by Letters Patent all forms of the invention falling within the scope of the following claims.

We claim:

1. Apparatus for placing an explosive charge beneath the earth's surface comprising a drill pipe, a drill bit, said drill bit having an explosive charge connected thereto, a quantity of ignition cable disposed adjacent the lower end of the drill bit, means connecting one end of the cable to the lower end of the drill pipe, means connecting the other end of the cable to the explosive charge, housing means enclosing said cable and said explosive charge, and releasable means connecting said drill pipe to said drill bit.

2. In combination, a first pipe, a tubular receptacle of smaller cross sectional area than the pipe disposed inside the pipe and secured thereto, said receptacle being closed at its lower end and open at its top end, a closure for the upper end of the receptacle, said closure having a hole therethrough, a second pipe, a second tubular housing of

smaller cross sectional area than the second pipe disposed inside the second pipe and releasably secured thereto, a spool disposed in said housing, an ignition cable wound on the spool and connected thereto at one end, the other end of said cable passing through said hole in said closure for the receptacle, a detonator on said other end of the cable, an explosive charge in said receptacle, said detonator being buried in said charge, and releasable means coupling the upper end of the first pipe to the lower end of the second pipe.

3. In combination, a first pipe having an upper end of reduced diameter and a lower end of larger diameter, a second pipe of the same diameter as the lower end of the first pipe, means releasably connecting the top of the second pipe to the bottom of the first pipe, a ring secured in the lower end of the second pipe, a cylindrical housing inside of and concentric with the second pipe, said housing having a closed top and an open bottom, said housing having a smaller outer diameter than the inside diameter of the second pipe leaving an annular space therebetween, a plurality of spring fingers secured at their upper ends to said housing and having their lower ends pressing against the inside of the second pipe above said ring, a spool disposed in said housing with its axis vertical and its upper end secured to the top of said housing, a second ring secured in the lower part of said housing spaced from the lower end thereof, a third pipe, a bayonet joint coupling the top of the third pipe to the bottom of the second pipe, a cylindrical receptacle in the third pipe and concentric therewith, said receptacle having a smaller outside diameter than the inside diameter of the third pipe leaving an annular space therebetween, struts connecting said receptacle to said third pipe, said receptacle having a closed bottom, and means to close the top of said receptacle, the last said means having a hole therethrough, the top of said receptacle telescoping snugly inside of the bottom of said housing against the second ring.

4. The combination of claim 3 with a flexible line connected at one end to the top of said housing and at the other end to the interior of one of said first and second pipes.

5. The combination of claim 4 with a rod extending across the lower part of said first pipe, a swivel connected to said other end of the flexible line, and a ring connected to said swivel and passed over said rod for sliding motion relative thereto.

6. Apparatus for placing an explosive charge beneath the earth's surface comprising a drill pipe having a water passage therethrough, a drill bit assembly having a water passage therethrough, releasable means connecting said drill pipe to said drill bit assembly with their water passages in longitudinal alignment, said drill bit assembly having an explosive charge secured therein, a length of ignition cable within said water passages, said ignition cable being connected at one end to said explosive charge and at the other end to said drill pipe, and shielding means adapted to protect said ignition cable and said explosive charge from fluid flow through said water passages.
